(57) **CLAIM**

The ornamental design for an electronic fly trap, as shown and described.

DESCRIPTION

FIG. 1 is a front perspective view of an electronic fly trap showing my new design in an open position;

FIG. 2 is a left side elevational view thereof;

FIG. 3 is a right elevational view thereof;

FIG. 4 is a top plan view thereof;

FIG. 5 is a front elevational view thereof, shown in an open position;

FIG. 6 is a rear elevational view thereof;

FIG. 7 is a bottom plan view thereof; and,

FIG. 8 is a front perspective view, with the broken line showing of environment being for illustrative purposes only and forming no part of the claimed design.
